UNITED STATES PATENT OFFICE

134,998

DESIGN FOR A COVER FOR BIBLES

Jack Galter, Chicago, Ill.

Application November 16, 1942, Serial No. 108,795

Term of patent 3½ years

To all whom it may concern:

Be it known that I, Jack Galter, a citizen of the United States of America, residing at 711 West Lake Street, Chicago, Illinois, have invented a new, original, and ornamental Design for a Cover for Bibles, of which the following is a specification, reference being had to the accompanying drawing, forming a part hereof.

Fig. 1 is a front elevational view of a cover for Bibles embodying my new design; Fig. 2 is an edge view; Fig. 3 is a bottom edge view of the same, and Fig. 4 is a plan view of the inside thereof on a smaller scale.

I claim:

The ornamental design for a cover for Bibles, substantially as shown.

JACK GALTER.
